UNITED STATES PATENT OFFICE.

OTTO B. DREUSIKE, OF SAN FRANCISCO, CALIFORNIA.

SLIDING AND REVERSING WINDOW.

Application filed April 6, 1921. Serial No. 459,086.

To all whom it may concern:

Be it known that I, OTTO B. DREUSIKE, a citizen of the United States, and resident of the city and county of San Francisco, State of California, have invented new and useful Improvements in Sliding and Reversing Windows, of which the following is a specification:

My invention is particularly adapted to metal sash frames and has for its object the provision of means whereby the window sash at all times is held against rattling or vibration but is free to operate both for raising and lowering or for turning to any desired degree, as, for example, reversing, so that the weather side of the window may be cleaned from the inside of the room.

The objects of this invention are the securing of the greatest degree of safety for washing the window combined with simplicity, efficiency of operation, perfect tracking and elimination of all vibration.

By referring to the accompanying drawings my invention will be made clear.

Fig. 1 shows a pair of sash mounted in a window frame employing my invention and shows diagrammatically the manner of hanging the sash.

Fig. 2 is a fragmentary showing of one of the sash in a partially tilted position, the inner side of the window frame being cut away for the purpose of showing the sash and its cooperating parts.

Fig. 3 is a detail front view of one side of one sash with its tracking mechanism shown in section and with the window turned into half reversed position and with the frame partly broken away.

Fig. 4 is a detail cross section of the upper and lower portions of the tracking mechanism showing the manner in which it operates to maintain perfect tracking at all times and is a full size showing of certain parts shown in Fig. 3.

Fig. 5 is a full size detail cross section of the sash pivot and its locking means.

Fig. 6 is a front view of Fig. 5.

Fig. 7 is a full size cross section through the sash 2, track member 7 and shoe 9 in their position of alignment when the sash is in closed position, and is taken on the line V--VII of Figs. 1, 5.

Throughout the figures similar numerals refer to identical parts.

55 The window frame is shown by the numeral 1 in which are mounted the lower sash

2 and upper sash 3 which are substantially duplicates of each other and which are each provided with a track bar 7, and shoe 9, on each side, and are counterbalanced with respect to each other by being hung on the same cords or chains 4, 5, operating over pulleys at the top of the window frame 1. Each of the sash is pivoted at its center and on each side by pivots indicated as at 6 and 31, the said pivots being supported in tracking bars as 7. The bars 7 are adapted to slide in ways 8 and mounted telescopically within each tracking bar or slide member 7 is the shoe 9, whose face 29, at all times seats against the bottom of the ways 8 through the action of the chain 4 against certain of the parts as described below. The pivot 6 extends through the opening 10 in the track member 7 and when turned into the position 75 as shown in Fig. 5, at which time the sash is substantially horizontal, the flange end 11 of the pivot 6 extends across the axis of the elongated opening 10. However, to insure the locking of the pivot 6 within the member 7, I provide the locking strip 12 which is mounted slidably against the inner wall of member 7 and held therein by the fastenings 13 and 14 with a permissible longitudinal movement provided by the slots 15, 85 16. In the front of the member 7, I provide a slot 17 and opposite thereto and within the range of the said slot the hole 18 so that a pointed instrument may be introduced into the hole 18 through the slot 17 and the lock plate 12, raised or lowered. In Fig. 6 the said plate is shown in its raised position and when depressed, as described, it advances over the shank of the pivot 6 to the dotted position shown at 19, at which time 95 the lateral openings 10, through which the head 11 has been introduced are closed by the ears or projections 20, 21, so that the pivot 6 is securely locked to the slide member 7. The shoe 9 which slides within the member 7, see Fig. 7, is loosely linked thereto by the links 22, 23, which swing from pivots 24, 25, mounted in the shoe 9, and from the pivots 26, 27 in the slide bar 7. The shoe 9, the slide bar 7 and the sash 2 105 are then suspended by the chain 4 which I prefer to secure to the rivet or cross member 26, which latter is removable, in the slots 28 in each side of, and therefore bridges, the member 7. The chain 4 now passes upward 110 and is reaved on the inside of the shoe pivots 24, 25 and on the outside of the slide

100

110

pivot 27. The tension of the chain 4, caused by the weight of the sash 3, see Fig. 1, therefore forces the shoe 9 outwardly with a component of pressure derived from the chain 5 tension acting on rivets 24, 25 in the shoe 9; thus insuring at all times pressure from the face 29 of the said shoe against the bottom of its way 8. It will now be seen that the mechanism above described secures at all 10 times the proper guiding of the sash 2 by the shoes 9 and bars 7, by contact with the bottom of the ways 8. If the sash be suspended as shown in Fig. 1; that is, if member 2 and member 3 counterbalance each other, the 15 raising of the sash 2 is accompanied by the lowering of the sash 3; and at any time either of the sash may be rotated with respect to the window frame 1 and about its pivots as 6, 31. To hold the sash in vertical alignment with the ways 8, during such 20 times as they are not rotated, I form the member 7 and the cooperating side of the sash of convex and concave curvature, respectively, and make the shank 6 of the pivot 25 sufficiently long so that when the sash shown in position in Fig. 7, is rotated into position shown in Fig. 5 the concave face of the sash rides up on the convex face of the tracking member 7 by forcing the member 30 7 to move toward the bottom of its respec-

tive way 8, and causing the chain 4 to take the position shown in Fig. 4. This introduces a friction element between the sash 2 and the member 7 sufficient to hold the sash 35 in any position in which it is turned, and when it is turned into alignment with the member 7 the concave surface of sash 2 seats over the convex surface of member 7, thus locking the sash 2 in relative alignment with the member 7. 40

I claim:

In a window structure comprising a frame provided with a guideway, and a sash movable therealong; the combination with a stile of said sash of a tracking bar slidable 45 in said guide-way, and having a wall normally in contact with the adjacent wall of said stile, one of said walls having a concave surface and the other a convex surface normally disposed therein; a headed pivot extending from said convex surface into said concave surface and separably uniting said sash and said tracking bar, but permitting said tracking bar to move laterally in said guideway; and vertically sliding means carried by and conforming to said concave wall for straddling said pivot to prevent withdrawal of the same and reinforcing said concave wall adjacent to said pivot. 50 55

OTTO B. DREUSIKE.
